SCRUBBING MITT

Morris E. Epstein, Swampscott, and Earl H. Barry, Marblehead, Mass., assignors to Bay State Mop Wringer Co., Inc., Wilmington, Mass., a corporation of Massachusetts

Filed Oct. 22, 1965, Ser. No. 87,754

Term of patent 14 years

(Cl. D9—2)

FIG. 1

FIG. 2

FIG. 3

FIG. 1 is a front elevational view of a scrubbing mitt showing our new design;

FIG. 2 is a side elevational view thereof;

FIG. 3 is an elevational view of the closed end thereof; and

FIG. 4 is an elevational view of the opposite open end thereof.

The side not shown has substantially the same appearance as the side shown.

The drawing is shaded to indicate contrast.

We claim:

The ornamental design for a scrubbing mitt, substantially as shown and described.
